UNITED STATES PATENT OFFICE.

JOHN L. MOHUN, OF OMAHA, NEBRASKA.

LOCOMOTIVE.

Application filed July 16, 1923. Serial No. 651,828.

To all whom it may concern:

Be it known that I, JOHN L. MOHUN, a citizen of the United States, residing at Omaha, in the county of Douglas and State of Nebraska, have invented a certain new and useful Improvement in Locomotives, of which the following is a full, clear, concise, and exact description, reference being had to the accompanying drawings, forming a part of this specification.

This invention relates to improvements in locomotives.

In the present day operation of large, modern locomotives, numerous auxiliary devices are employed on the locomotive, as for instance, the air pump, stoker engine, dynamo turbine, and so on. Under the conditions which obtain, the steam consumption by these auxiliaries amounts to 20 to 25% of the total generated steam and it is highly desirable, for the purpose of economizing on fuel consumption, that these auxiliary devices be operated by super-heated steam, such as is used for driving the locomotive, so far as it is possible to do so, and to use the saturated steam for the auxiliary devices only when necessary.

I am aware that attempts to accomplish the foregoing have heretofore been made. Such former attempts as I am aware of may be divided into two general classes. One of these involves the location of the main throttle valve between the usual super-heater and the cylinder chest. By suitable piping and valve controls, it is possible with this arrangement to supply super-heated steam to the auxiliary devices at all times, but this arrangement is not readily adapted to modern types of locomotives wherein it is customary to locate the super-heater at the front end of the boiler. With the arrangement referred to, it is obvious that if the throttle valve is located between the super-heater and the cylinder chest, the throttle valve must be of special construction to enable it to withstand the high temperature of the superheated steam and, furthermore, the location of the throttle valve so far forward on the locomotive necessitates more complicated throttle operating rods and levers running from the cab. Such an arrangement is very costly even on new locomotives and the cost of installing such an arrange-

ment on existing locomotives is so excessive as to practically prohibit its consideration.

The other arrangement heretofore suggested retains the main throttle valve between the steam dome and the super-heater with the usual saturated steam supply to turret in the cab, and from which the saturated steam is distributed to the various auxiliary devices. In this last arrangement referred to, however, the super-heated steam for the auxiliary devices is supplied from the super-heater individually to the various auxiliary devices without being transmitted through the turret. With such an arrangement, it will be evident that more separate lines of pipes and more control and check valves are required, thus increasing both the cost of original installation and the cost of maintenance because of the great number of parts involved. Furthermore, such an arrangement involves a departure from the customary manner of controlling or shutting off the supply of steam, either saturated or super-heated, to the auxiliaries, which is ordinarily done by the engineer at the usual turret located in the cab.

One object of my invention is to provide an arrangement for locomotives of the so-called "super-heated" type, such as are embodied in the well known "Mountain" and "Mikado" types of locomotives, wherein all of the steam required for the auxiliary devices, whether saturated or super-heated, depending upon the conditions of operation, is directly supplied to the turret before being distributed to the various auxiliary devices.

Another object of the invention is to provide an arrangement in a locomotive whereby super-heated steam is supplied to all of the auxiliary devices whenever the locomotive is running and, upon shutting off the supply of super-heated steam to the locomotive cylinders, means are automatically made effective for then supplying the auxiliary devices with saturated steam to the end of increasing the efficiency of the locomotive by reducing fuel consumption.

More specifically, an object of my invention is to provide an arrangement of the character generally indicated in each of the two preceding paragraphs which may be readily incorporated in new locomotives without materially increasing cost or ap-

plied to existing locomotives of the larger, modern type without any material modification of the usual arrangement of parts and at relatively small expense.

5 A further specific object of the invention is to provide an arrangement of the character above indicated, wherein is employed an auxiliary valve for the saturated steam supplied from the usual steam dome to the turret, said auxiliary valve being located in the steam dome whereby the same is readily accessible for inspection or repair, as in the case of the main throttle valve as at present.

10 The invention furthermore consists in the improvements in the parts and devices and in the novel arrangements of the parts and devices herein shown, described and made the subject matter of claims.

15 In the drawings forming a part of this specification, Figure 1 is a top plan view, more or less diagrammatic, with certain parts of the boiler front extension in section, and illustrating the general arrangement of my improvements as applied to a large, modern locomotive. Figure 2 is a side elevation of a portion of a large, modern locomotive and illustrating the arrangement shown in Figure 1 as incorporated therein. In Figure 2, certain parts of the locomotive 20 are broken away in order to more clearly illustrate features of the construction and in both Figures 1 and 2, parts are omitted to better accommodate the views on the sheet. Figure 3 is an enlarged side elevational view 25 illustrating the main throttle valve, auxiliary valve and operating parts, illustrated in Figures 1 and 2. And Figure 4 is a view similar to Figure 3, illustrating a somewhat different embodiment of the main throttle valve, auxiliary control valve and operating devices therefor.

30 Referring first to the construction illustrated in Figures 1, 2 and 3, the locomotive is shown as having the usual boiler proper 10, steam dome 11, front boiler tube sheet 12, stack 13, front extension 14, super-heater header 15, steam turret 16, and outer sheathing or casing 17.

35 As customary in large, modern locomotives, the main throttle valve indicated conventionally at 18, is located within the usual steam dome 11 and the super-heater header is disposed forwardly of the front tube sheet 12. Saturated steam is supplied from the steam dome through the throttle valve 18 and longitudinally and centrally disposed supply pipe 19 to the super-heater header. The latter, illustrated conventionally, in turn supplies the super-heated steam 40 through two large pipes or conduits 20--20, one on each side of the locomotive, to the usual steam chests, which I do not deem it necessary to illustrate. The throttle valve 18, illustrated conventionally, is of the usual "balanced" type and the valve proper 21

thereof is actuated in a vertical direction through laterally extended pins 22 rigid therewith, links 23, bell crank lever 24 and throttle rod 25, the latter leading back to the cab in the usual manner.

45 In the large, modern locomotives, it is now customary to run two pipes 27—27 from the steam dome to the steam turret for the reason that it is difficult to use a single large pipe on account of interfering with the usual stays. In carrying out my invention when two pipes 27 are used, I therefore employ an auxiliary control valve 28 in connection with each of said pipes 27. The control valves 28 are also illustrated conventionally and are of the usual "balanced" type, the same being made of appreciably lesser size than the throttle valve 18. Each of the auxiliary control valves 28 includes a main casing having suitable lugs or ears 29 by which it may be readily, but detachably, mounted on the throttle valve 18 so that both valves are located within the steam dome or steam chamber and therefore readily available for examination or repairs, as will be obvious.

50 Each of the auxiliary valves includes a valve proper 30 to which is pivotally connected a lever 31 fulcrumed on a suitable extension 32 formed integral with the auxiliary valve casing. The opposite end of each lever 31, is pivotally connected to the respective pin 22, as best indicated in Figure 3. By reason of vertically elongated slots 26, provided in each lever 31, a predetermined amount of lost motion is allowed between the levers 31 and links 23 because of the greater movement necessary, of the throttle valve proper 21 as compared with the smaller auxiliary valves proper 30. The throttle valve proper 21 and the auxiliary valves proper 30 are so connected with the lever 31 that, when the throttle valve 21 is closed, the auxiliary valves proper 30, are open and vice versa. From the preceding description, it will be seen that, when the engineer opens the main throttle valve, the auxiliary valves 28 will be closed or shut off, thus supplying saturated steam to the super-heater header and shutting off the supply of saturated steam to the turret. Conversely, when the throttle valve is closed, thus shutting off the supply of saturated steam to the super-heater header, saturated steam will be supplied to the turret.

55 To effect supply of super-heated steam to the turret when the locomotive is running, that is, when the throttle valve 18 is open, I run two pipes 33, one on each side of the locomotive, from the super-heater header to the turret, as best illustrated in Figure 1. Preferably, each of these pipes has included therein, adjacent the super-heater header, a shut-off valve 34. Also included in each of the pipes 33 and preferably adjacent

the turret, is a check valve 35 adapted to permit the passage of super-heated steam therethrough to the turret, but operating to prevent saturated steam passing therethrough in the reverse direction when super-heated steam is not being supplied to the turret.

I have not deemed it necessary to illustrate any of the particular auxiliary steam consuming devices, but, as will be appreciated by those skilled in the art, the same will have the steam distributed thereto from the turret through respective pipes as indicated at 36, and in which will be included the usual 15 shut-off valves when it is desired to prevent the passage of any steam to any particular auxiliary device.

From the preceding description, considered in connection with the drawing, it 20 will be seen that, when the locomotive is working and saturated steam is being supplied to the super-heater, all of the super-heated steam for the auxiliary devices will be supplied direct to the turret and the 25 source of saturated steam to the turret shut off. When the locomotive is not working, that is, when the locomotive is drifting or is stationary, and the throttle valve 18 is closed, all of the saturated steam required 30 for the auxiliary devices is supplied to the turret from which it may be distributed to said devices, while at the same time saturated steam is prevented from flowing to the super-heater by the check valves 35-35.

Referring to the construction illustrated in Figure 4, 118 indicates the throttle valve having a valve proper 121. The auxiliary valve is indicated at 128, the same having a valve proper 130. The throttle valve proper 121 is operated through suitable links 123, which are pivotally connected at their lower ends to a bell crank lever 124, one arm of which 124^a is pivotally connected to the usual throttle rod 125. In this construction, 45 the bell crank 124 is provided with an additional arm 50 having a rounded end 51 which engages an anti-friction and weight roller 52 attached to the lower end of a rod 53 that is connected at its upper end to the auxiliary valve proper 130. Said rod 53 is suitably guided by guide lugs 54 formed on a depending flange of the auxiliary valve casting. In the modification shown in Figure 50 4, only a single auxiliary valve is employed with one pipe 127 leading to the turret as this construction will be preferable in some types of locomotives. In this modification, as clearly shown in Figure 4, the throttle valve 121 is closed and the auxiliary valve proper 130 is open. When the throttle valve is opened by pulling the rod 125 toward the left as viewed in Figure 4, it is obvious that the bell crank lever arm 50 will move downwardly thereby permitting 55 the auxiliary valve proper 130 to fall and

close the auxiliary valve. In this connection, it will be observed that, on account of the arrangement of crank arm 50 and roller 52, the necessary lost motion between the auxiliary and throttle valve proper is accommodated since the arm 50 can continue its downward movement after the auxiliary valve proper 130 is closed.

From the preceding description, it will be seen that my improvements may be readily incorporated in new locomotives without material increase in cost and also that they may be incorporated in existing locomotives without substantial change in the arrangement of existing parts, my improvements involving merely the addition of the pipes 33 between the super-heater and the turret and the introduction of the auxiliary valves 28 within the saturated steam supply pipes 27 for the turret, together with suitable operating mechanism between the throttle valve proper 21 and the auxiliary valves proper to effect their simultaneous, but opposite movements.

I have herein shown and described what I now consider the preferred manner of carrying out my invention, but the same is merely illustrative and I contemplate all changes and modifications that come within the scope of the claims appended hereto.

I claim:

1. In an apparatus of the character described having a source of saturated steam supply and a main steam consuming device, the combination with a super-heater; of means for supplying said super-heater with steam from said source of steam supply; a main control valve for said means; means adapted to supply an auxiliary steam consuming device with saturated steam from 100 said source of supply; means for supplying super-heated steam to said auxiliary steam consuming device, an auxiliary control valve for said means for supplying the saturated steam located adjacent said main control valve; and manually operable means for actuating said main control valve, said auxiliary control valve operating to supply saturated steam when said means for supplying super-heated steam is cut off, said auxiliary control valve being operable in predetermined relation with said main control valve so that when one is open, the other is closed and vice versa.

2. In an apparatus of the character described having a source of saturated steam supply and a main steam consuming device, the combination with a super-heater; of means for supplying said super-heater with steam from said source of steam supply; a main control valve for said means; means for supplying an auxiliary steam consuming device with super-heated steam, means adapted to supply said auxiliary steam consuming device with steam directly from said

source of supply; an auxiliary control valve for said last named means located adjacent said main control valve; and manually operable means for actuating said main and auxiliary control valves simultaneously, but oppositely.

3. In a locomotive having a super-heater, a throttle controlled pipe supplying it with steam from the boiler, and a turret from which steam is adapted to be distributed to an auxiliary steam consuming device; the combination with a valve controlled pipe for supplying said turret with steam from the boiler; of a super-heated steam direct supply pipe from said super-heater to said turret; and means operable to close said valve when the throttle is open and to open said valve when the throttle is closed.

4. In a locomotive having a saturated steam supply chamber, super-heater, turret, said turret being arranged to supply steam to an auxiliary steam consuming device; means, automatically operable, for supplying said turret with super-heated steam only when the locomotive is working and with saturated steam only when the locomotive is not working including, a throttle controlled conduit between said chamber and super-heater.

5. In a locomotive having a saturated steam supply chamber, super-heater, turret, said turret being arranged to supply steam to an auxiliary steam consuming device; means, automatically operable, for supplying said turret with super-heated steam only when the locomotive is working and with saturated steam only when the locomotive is not working, including a valve controlled conduit between said chamber and turret, a throttle controlled conduit between said chamber and super-heater and a check controlled conduit between said super-heater and turret.

6. In a locomotive having a steam chamber, super-heater, turret, said turret being arranged to supply steam to an auxiliary steam consuming device; means for supplying said turret with super-heated steam only when the locomotive is working and with saturated steam only when the locomotive is not working including, a saturated steam supply pipe from said chamber to the super-heater having a throttle valve included therein located within the chamber, and a saturated steam supply pipe from said chamber to the turret and having included therein an auxiliary control valve also located in the chamber.

7. In a locomotive having a steam chamber, super-heater, turret, said turret being adapted to supply an auxiliary steam consuming device; means for supplying said turret with super-heated steam only when the locomotive is working and with saturated steam only when the locomotive is not

working including, a saturated steam supply pipe from said chamber to the super-heater having a throttle valve included therein and located within the chamber, a saturated steam supply pipe from the chamber to the turret having an auxiliary control valve included therein and located also within the chamber, and operative connections between the valves proper of said throttle and auxiliary valves arranged to simultaneously but oppositely actuate said valves proper when the throttle valve is operated.

8. In a locomotive having a steam chamber, super-heater, turret, said turret being arranged to supply an auxiliary steam consuming device; means for supplying said turret with super-heated steam only when the locomotive is working and with saturated steam only when the locomotive is not working including, a throttle valve comprising a casing and valve proper located within the chamber, a supply pipe from said throttle valve to the super-heater, an auxiliary valve comprising a casing and a valve proper located within said chamber and detachably mounted on the throttle control valve, a supply pipe from said auxiliary valve to the turret, and a pipe communicating with said super-heater and turret having a check valve included therein.

9. In a locomotive having a steam chamber, super-heater, turret said turret being arranged to supply an auxiliary steam consuming device; means for supplying said auxiliary device with super-heated steam when the locomotive is working and with saturated steam when the locomotive is not working including, a saturated steam supply pipe from said chamber to the super-heater having a throttle valve included therein and located within the chamber; and a saturated steam supply pipe leading from said chamber to the turret and having included therein an auxiliary control valve also located in the chamber.

10. As an article of manufacture, a two-way valve comprising: a main valve having a valve proper and a valve casing provided with admission and delivery means; an auxiliary valve having a valve proper and valve casing provided with admission and delivery means whereby the steam may be taken from the same steam chamber and delivered separately through either valve to different steam consuming devices; and operating mechanism associated with said two valves proper arranged to move each of said valves proper to open and closed position, said operating mechanism effecting closure of one of said valves proper and simultaneous opening of the other and vice versa.

11. In a locomotive having a steam chamber, super-heater, turret for supplying steam to auxiliary devices; means for supplying the turret with super-heated steam when the

locomotive is working and with saturated steam when the locomotive is not working including: a saturated steam supply pipe from said chamber to the super-heater having the throttle valve included therein; and a pair of saturated steam supply pipes leading from said chamber to the turret and each having included therein, an auxiliary control valve.

12. In a locomotive having a super-heater, a throttle controlled pipe supplying it with steam from the boiler; a turret from which steam is distributed to auxiliary device; the combination with a pair of pipes for supplying said turret with steam from the boiler, each of said pipes having a control valve included therein; of a super-heated steam direct supply pipe from said super-heater to said turret; and means operable to close said valves when the throttle is opened and to open said valves when the throttle is closed.

13. In a locomotive having a saturated steam supply chamber, super-heater, and turret for supplying auxiliary steam consuming devices; means, automatically operable, for supplying said turret with super-heated steam only when the locomotive is working and with saturated steam only when the locomotive is not working including, a throttle controlled conduit between said chamber and super-heater, and duplicated valve controlled conduits between said chamber and turret.

14. In a locomotive having a steam cham-

ber, the combination with a main throttle 35 disposed within said chamber and including a valve proper; of an auxiliary valve also located in said chamber and including a valve proper; and manually operable means for actuating both of said valves proper to positively open and close the same, said means operating said main and auxiliary valves proper simultaneously, but oppositely, said means including therein a lost motion device between said throttle valve proper and auxiliary valve proper to permit greater movement of the throttle valve proper than the auxiliary valve proper.

15. In a locomotive having a saturated steam supply chamber, super-heater, and 50 turret, said turret being arranged to supply auxiliary steam consuming devices; of a pipe for supplying said super-heater with saturated steam; a main valve for regulating the supply of steam to said super-heater; means 55 for supplying saturated steam to said turret; an auxiliary valve for controlling the passage of saturated steam to said turret; means connecting said super-heater with said turret; and operating mechanism associated 60 with said main and auxiliary valves to effect closure of one of said valves and simultaneous opening of the other, and vice versa.

In witness that I claim the foregoing I have hereunto subscribed my name this 3rd 65 day of July 1923.

JOHN L. MOHUN.
